UNITED STATES PATENT OFFICE

2,616,278

TEXTILE MATERIAL

Thomas H. Hilliard, Drummondville, Quebec,
Canada, assignor to Canadian Celanese Limited,
a corporation of Canada

Application March 17, 1949, Serial No. 81,997

2 Claims. (Cl. 68—13)

1

This invention relates to textile materials, and relates more particularly to the preparation of partially saponified staple fibers having a basis of cellulose acetate or other organic acid ester of cellulose.

It is common practice in the textile art to convert continuous filaments of cellulose acetate or other organic acid ester of cellulose to staple fibers and to spin the fibers so produced into yarn. In order to improve the spinability of such staple fibers and to enhance the textile properties of the yarns produced therefrom, the staple fibers are often partially saponified. While the saponification may be carried out by batch processes, it has been found that this method of saponification is not satisfactory since the properties of the partially saponified fibers may vary from batch to batch and, moreover, batch methods necessitate much handling of the staple fibers.

It is an important object of this invention to provide a continuous process for preparing partially saponified staple fibers having a basis of cellulose acetate or other organic acid ester of cellulose, which will be free from the foregoing and other disadvantages and which will be especially simple and efficient in operation.

Another object of this invention is to provide a continuous process for preparing partially saponified staple fibers wherein staple fibers having a basis of cellulose acetate or other organic acid ester of cellulose are saponified while being carried along in a saponification medium.

Still another object of this invention is the provision of improved apparatus, which is simple in construction and expeditious in use, for the treatment of fibrous materials whereby fibrous materials in a liquid medium are subjected to the desired treatment while being carried from point to point by said liquid medium.

Still another object of this invention is the provision of improved apparatus for the treatment of fibrous materials wherein an enclosed passageway is employed for conveying the fibrous materials from point to point and in which enclosed passageway the fibrous materials are subjected to the desired treatment.

Other objects of this invention, together with certain details of construction and combinations of parts, will be apparent from the following detailed description and claims.

The present invention comprises the cutting of a bundle or tow of continuous filaments into the form of staple fibers, wetting the staple fibers as they are formed with a treating medium, adding

2

a further quantity of the treating medium to the wet staple fibers to form a mixture therewith, passing the said mixture through an enclosed passageway wherein the desired treatment of the staple fibers takes place, and thereafter separating the staple fibers from the treating medium and washing and drying the same.

In accordance with this invention, continuous filaments having a basis of simple organic acid esters of cellulose, such as cellulose acetate, cellulose propionate and cellulose butyrate and mixed organic acid esters of cellulose, such as cellulose acetate-propionate and cellulose acetate-butyrate, of any desired denier are formed into a bundle or tow and cut into staple fiber length by suitable cutting means. Preferably the continuous filaments are crimped, prior to being cut into staple lengths, by any suitable crimping means such as a stuffing box or serrated rolls. The staple fibers produced are then saponified by forming a mixture thereof with a saponification medium, the saponification being effected while the mixture of staple fibers and saponification medium is moving through an enclosed passageway. The mixture of staple fibers and saponification medium should have a fiber content of less than about 2% by weight since with a higher fiber content the mixture will not flow freely and, in addition, the saponification medium will not have access to all of the staple fibers and may saponify them non-uniformly.

The saponification medium may comprise an aqueous solution of sodium hydroxide, sodium carbonate, potassium hydroxide, potassium carbonate, trisodium phosphate or other alkaline material having a concentration of between about 0.8 and 1.5% by weight based on sodium hydroxide. In addition to the alkaline material, the saponification medium may contain from about 1.0 to 2.0% by weight of a buffering agent, such as sodium acetate, sodium propionate or sodium butyrate, to control and make more uniform the action of the saponification medium on the staple fibers. During the treatment of the staple fibers, the saponification medium is preferably maintained at a temperature of between about 80 and 90° C. for best results. The degree of saponification of the staple fibers may be controlled by varying the composition, concentration and temperature of the saponification medium, and also by adjusting the time of treatment, e. g. by regulating the speed at which the staple fibers and saponification medium are conveyed through the enclosed passageway or by altering the length of said passageway.

After the staple fibers have been saponified, they are separated from the saponification medium, washed to free them from the residue of said medium and dried. They are then ready to be spun into yarn.

A preferred embodiment of the apparatus of my invention is diagrammatically illustrated in the accompanying drawings, in which

Fig. 1 is a front elevational view of the feed end of an apparatus for preparing and saponifying staple fibers having a basis of cellulose acetate or other organic acid ester of cellulose.

Fig. 2 is a front elevational view of the discharge end of the apparatus shown in Fig. 1.

Fig. 3 is a plan view of the portion of the apparatus shown in Fig. 1.

Fig. 4 is a plan view of the portion of the apparatus shown in Fig. 2.

Fig. 5 is a detail view, on an enlarged scale, of the centrifugal cutters that convert the tow to staple fibers.

Fig. 6 is a detail view, on an enlarged scale, showing the baffle plates that impart turbulence to the mixture of saponification medium and staple fibers, being conveyed through the passageway, and

Fig. 7 is a view in section taken on the line 7-7 in Fig. 6, in the direction of the arrows.

Like reference numerals indicate like parts throughout the several views of the drawings.

Referring now to the drawings, the reference numeral 11 designates crimped tows of continuous filaments of cellulose acetate or other organic acid ester of cellulose, which are led from tow cans 12 over guide bars 13 and 14 to a guide bar 15 of a tow tightener, or tension device, indicated generally by reference numeral 16. The tow tightener 16 comprises guide bars 17, 18 and 19 around which the tows 11 pass to form loops 21, which serve to maintain the desired tension on said tows. After passing over the guide bar 19, the tows 11 pass under pulleys 22 and are guided by pulleys 23 onto feed rollers 24, which feed rollers are positively driven by means of a motor 25 operatively connected thereto by a belt (not shown) within the housing 25'. The tows 11, after passing around the feed rollers 24, are guided by pulleys 26 and 27 to centrifugal cutters, indicated generally by reference numeral 28.

The centrifugal cutters 28 comprise casings 29 in which are positioned disks 31 mounted on shafts 32 journaled in bearings 33. The disks 31 are rotated at a high speed by any suitable means (not shown) through the shafts 32 by belt drives 34 trained around pulleys 35. The tows 11 enter the cutters 28 through apertures 36 in the casings 29 and are threaded into radially extending passageways 37 in the disks 31. As the disks 31 revolve, the tows 11 are drawn outwardly through the passageways 37 by centrifugal force, and the ends of said tows are severed into staple fiber form by cutting blades 38. By adjusting the speed of the feed rollers 24 relative to the speed of the disks 31, the length of the staple fibers produced may be varied readily over a wide range.

Immediately after being formed, the staple fibers are sprayed and thoroughly wet with a saponification medium from conduits 39 that extend through the casings 29 of the centrifugal cutters 28. The wet staple fibers then drop from the casings 29 into a funnel 41 leading to a horizontally disposed enclosed passageway, indicated generally by reference numeral 42, in which the saponification is effected. The funnel 41 is positioned in a tank 43 to which a saponification

medium is pumped from a storage tank 44 through a conduit 45 by means of a pump 46. The saponification medium also flows from the conduit 45 to the conduits 39 in the centrifugal cutters 28 through branch conduits 47. As the saponification medium enters the tank 43, it is mixed thoroughly by baffles 48 and 49 positioned therein, and then passes over heating coils 51, through which a heating fluid such as steam, is circulated, to control the temperature of said saponification medium. The level of the saponification medium in the tank 43 is regulated by an overflow pipe 52 that discharges through a conduit 53 back to the storage tank 44.

The saponification medium also overflows through apertures 54 in the funnel 41 into the enclosed passageway 42 and mixes with the staple fibers therein. The enclosed passageway 42, which comprises a plurality of pipe sections 55 fastened together by couplings 56, is kept full by having its discharge end 57 raised above its feed end 58. As the saponification medium and staple fibers pass through the enclosed passageway 42, turbulence is imparted to the saponification medium by curved baffle plates 59, which may be positioned at each of the couplings 56. This insures a thorough wetting of the staple fibers by the saponification medium, and a rapid and uniform saponification of said fibers.

After passing through the enclosed passageway 42, the saponification medium and staple fibers are discharged between baffles 60 onto a positively driven, wire mesh belt 61 which is trained around positively driven rollers 62 and 63 and idler roller 64. The wire mesh belt 61 permits the major portion of the saponification medium to drain from the staple fibers, and carries the staple fibers under a squeeze roll 65, which with roller 63 expresses more of the saponification medium from the staple fibers. The saponification medium drained from the staple fibers and expressed therefrom by the squeeze roll 65 is collected in a pan 66 and flows through a spout 67 to the storage tank 44 for further use. The strength of the saponification medium in the tank 44 is maintained constant by intermittent or continuous addition thereto of a concentrated solution of the saponification agent from tank 68. Similarly, the volume of the saponification medium in the tank 44 is maintained constant by intermittent or continuous addition thereto of a quantity of water from the tank 69. Valves 70 are provided in the lines for supplying the saponification medium and the water to regulate the feed thereof to the tank 44.

From the squeeze roll 65, the staple fibers pass between squeeze rolls 71 and 72 to express more of the saponification medium therefrom. The staple fibers then drop onto a positively driven wire mesh belt 73, which is trained around rollers 74 and 75, and idler 76. The wire mesh belt 73 carries the staple fibers under a series of water sprays 77 to wash the residue of the saponification medium therefrom. The staple fibers then pass under a squeeze roll 81 to express a portion of the wash water therefrom and are deposited by means of a positively driven roller 82 onto an endless belt 83. The liquid drained from the staple fibers is collected in a pan 84 and discharged as waste through a conduit 85. A shield 86 mounted above the endless belt 83 prevents the staple fibers from overshooting said belt.

The endless belt 83 is trained around rollers 88 and 89 and may be driven in either direction by means of a motor 91 operatively connected

thereto through a chain drive 92. The endless belt 83 drops the staple fibers into either of two conventional centrifugal extractors, indicated generally by reference numerals 93 and 94, positioned at opposite ends of said belt. The use of two extractors permits of continuous operation since, while one extractor is removing the water from the staple fibers therein, the other extractor may be loaded and vice versa. After the major portion of the water has been removed from the staple fibers, the extractors may be unloaded by means of suction from a wool type fan, which will open up the staple fibers to facilitate drying and discharge said fibers directly into a dryer (not shown) wherein they are dried. The dried staple fibers may then be sprayed with a spinning lubricant and spun into yarn either alone, or in admixture with fibers of other types.

Instead of removing the water from the staple fibers by means of the extractors 93 and 94, the staple fibers may be passed through a set of wringer rolls similar to the wringer rolls 71 and 72 directly as they drop off the endless wire mesh belt 73 to remove the water therefrom. After emerging from between said wringer rolls, the staple fibers may be dried and spun into yarn as set forth above.

The following example is given to illustrate this invention further:

Example

Crimped tows of cellulose acetate having a total denier of 288,000 and an acetyl value of 54.5%, calculated as acetic acid, are fed at the rate of 500 pounds per hour into the apparatus shown in the accompanying drawings. The staple fibers produced from this tow are treated in this apparatus for a period of 18 seconds with a saponification medium comprising an aqueous solution containing 0.975% by weight of sodium hydroxide and 1.7% by weight of sodium acetate maintained at a temperature of 90° C. The staple fibers are then separated from the saponification medium, washed and dried. The saponified staple fibers have an acetyl value of 44% calculated as acetic acid and possess excellent spinning properties.

While the process and apparatus of this invention have been described with particular reference to the preparation of partially saponified staple fibers having a basis of cellulose acetate or other organic acid ester of cellulose to which they are especially adapted, they may also be employed for the preparation of other types of staple fibers and for the treatment of various types of fibrous materials with liquids.

It is to be understood that the foregoing detailed description is given merely by way of illustration and that many variations may be made therein without departing from the spirit of my invention.

Having described my invention, what I desire to secure by Letters Patent is:

1. Apparatus for the treatment of fibrous material comprising, in combination with a cutter for converting continuous filaments into staple fibers, means adjacent to said cutter for spraying a liquid medium onto said staple fibers as formed, a tank positioned adjacent to said cutter for holding a liquid medium, a horizontally disposed, completely enclosed conduit, having its discharge end elevated with respect to the other end thereof, operatively connected to said tank for introducing additional liquid medium into said conduit concomitantly with said staple fibers whereby the liquid medium, having entrained therein the staple fibers, flows through said conduit, the construction arrangement being such that said conduit is maintained substantially completely filled with liquid medium during the operation of said apparatus.

2. Apparatus for the treatment of fibrous material comprising, in combination with a cutter for converting continuous filaments into staple fibers, means adjacent to said cutter for spraying a liquid medium onto said staple fibers as formed, a funnel positioned beneath said cutter for receiving the staple fibers and the liquid medium directly therefrom, a tank for holding a liquid medium in which said funnel is mounted, a horizontally disposed, completely enclosed conduit, having its discharge end elevated with respect to the other end thereof, operatively connected to said funnel, apertures in the walls of said funnel for admitting additional liquid medium into said funnel whereby the liquid medium flows into said funnel and through said conduit, and baffle plates positioned in said conduit for imparting turbulence to the liquid medium during its passage therethrough, the construction and arrangement being such that said conduit is maintained substantially completely filled with liquid medium during the operation of said apparatus.

THOMAS H. HILLIARD.
